UNITED STATES PATENT OFFICE.

HERBERT R. WEBBER, OF RED WING, MINNESOTA.

SEWER.

1,299,884.

Specification of Letters Patent.

Patented Apr. 8, 1919.

Application filed October 16, 1916. Serial No. 125,800.

To all whom it may concern:

Be it known that I, HERBERT R. WEBBER, a citizen of the United States, residing at Red Wing, in the county of Goodhue and State of Minnesota, have invented certain new and useful Improvements in Sewers, of which the following is a specification.

My invention relates to sewers and has for its object to provide a segmental block from 10 which the sewer may be built up in the field. A further object is to provide each block with longitudinal dovetailed grooves, which grooves when the blocks are placed in position form recesses adapted to be filled with 15 concrete or other similar substances to hold the blocks firmly secured together.

The full objects and advantages of my invention will appear in connection with the detailed description thereof and are particularly pointed out in the claims.

In the drawings, illustrating the application of my invention in one form,—

Figure 1 is an elevational sectional view of a sewer built up from my improved 25 blocks. Fig. 2 is a perspective view of a portion of the sewer drawn to a larger scale. Fig. 3 is an enlarged sectional view taken through one of the blocks.

My improved segmental sewer block is 30 best shown in Figs. 2 and 3. It comprises a pair of concentric segmental walls 10 and 11 connected together by a central radial partition 12 and similar but thinner side walls 13 and 14 which are positioned a short 35 distance from the edges of the block. The extreme ends of walls 10 and 11 are formed with inwardly-extending acute ridges 15, which together with the side walls 13 and 14 form dovetailed recesses 16 and 17 at 40 the sides of the blocks. The blocks may be made of tile or of concrete, as desired, and are formed open at the ends.

In constructing the sewer the blocks are placed in position upon a suitable form and 45 cement is inserted in the recesses formed by the grooves 16 and 17, as indicated at 20 in Figs. 1 and 2. The walls 13 and 14 are preferably formed convex to withstand any

pressure incurred by the cement within these grooves. Two complete rounds 18 and 19 of the blocks are laid, the joints being broken both circumferentially and longitudinally, as clearly indicated in Figs. 1 and 2. In this manner the blocks are firmly held together and form a substantial and 55 rigid structure.

The advantages of my invention are manifest. The sewer is able to withstand tensile as well as compressive stresses, so that the same will hold up in case the earth pressure 60 varies on different sides of the sewer. By the use of the double round of blocks the sewer is rendered tight even after the lining has become mutilated and the blocks 65 have become bare.

I claim:

1. A curved hollow block comprising two oppositely disposed concentric segmental walls, an outwardly curved wall connecting said segmental walls at each side of the block 70 and positioned a short distance from the edges of said segmental walls and inwardly extending acute ridges on the projecting portions of said segmental walls adjacent each of said outwardly curved walls to form 75 dovetailed recesses in conjunction with said curved walls.

2. A curved hollow block comprising two oppositely disposed concentric segmental walls, a central radial partition wall connecting said segmental walls, a thin outwardly curved wall connecting said segmental walls at each side of the block and positioned a short distance from the edges of said segmental walls, and inwardly extending acute ridges on the projecting portions of said segmental walls adjacent each of said outwardly curved walls to form dovetailed recesses in conjunction with said 85 curved walls.

In testimony whereof I affix my signature in presence of two witnesses.

HERBERT R. WEBBER.

Witnesses:

SAMUEL J. NELSON,
JOHN F. MERRILL.
